United States Patent Office

SAMUEL W. SOULE, OF MILWAUKEE, WISCONSIN.

Letters Patent No. 65,839, dated June 18, 1867.

NUMBERING MACHINE.

The Schedule referred to in these Letters Patent and making part of the same.

TO ALL WHOM IT MAY CONCERN:

Be it known that I, SAMUEL W. SOULE, of Milwaukee, in the county of Milwaukee, and in the State of Wisconsin, have invented certain new and useful improvements in "Numbering Machines;" and do hereby declare that the following is a full, clear, and exact description thereof, reference being had to the annexed drawings, and the letters of reference marked thereon, making a part of this specification.

Figure 1 is a side view of the machine.

Figure 2, a view of the base of the machine.

Figure 3, a front view of the swinging frame B, cylinder, and type-wheels.

Figure 4, an end view of the cylinder showing the ratchet-wheel S.

Figure 5, a section of the ratchets *e f* which lie upon the type-wheels; and

Figure 6, a plan view of the dog *d*.

My invention is intended for numbering bank bills, bonds, checks, and other papers or cloths. It is composed of a metallic frame, having an upright, A, base or foundation A¹, and stationary arm A², somewhat in the usual form of the ordinary hand-stamps. O represents the vertical shaft, having a suitable pad at its top, passes through the extremity of the arm A² and extends down near the base A¹. Attached to the lower end of this shaft is a metal plate, J, which has suitable ears so that the cylinder *a*, (by means of its shaft,) may be hung. This cylinder is composed of a series of circular wheels, called type-wheels, which have numbers formed on their faces and placed at suitable distances from each other, and a ratchet-wheel, S, which is placed at the sides of the wheels for operating the attached type-wheel. The shaft supporting the cylinder *a* extends beyond the ears of the bent plate J, for connecting a swinging-frame, B, which is in turn pivoted to a metal frame, C, which is pivoted and has its bearings in the arm A², just in the rear of shaft O. E represents a pendent arm, pivoted at its lower extremity to a slotted plate, F, which plate is pivoted to the lower end of the shaft O. G are two curved bars extending near the base A¹, and which are connected at their forward ends to the roller-frame H. It will be seen that the pendent arm E and plate F support the roller-frame H, by means of the arms G, as before described. R is the ink-roller, secured to the front end of frame H, while there is a smaller roller K at the rear end of said frame, as seen, which rests upon the annular notched plate M, which is diagonally placed from the lower portion of the standard A to the base A¹. The ink-roller R is so placed that it may pass under the numbers on the wheels at the front, and is prevented from displacing the wheels by the guard W. *c* is a spring at the rear end of the frame H, which catches in the notches and revolves the table M, for regulating the ink upon the roller R after the smoothing by the small roller K, as will be hereinafter set forth. The type-wheels *v v v*, fig. 3, are separated by thin metal strips permanently fixed on the cylinder, in order that each wheel may revolve separately without moving the adjoining wheel, and are rotated by means of a notched dog, *d*, which is secured in the frame B. The frame B is provided with a dove-tailed groove, into which is placed a metallic plate in a vertical position, so that its lower end will rest upon the type-wheels. This plate with its notches acts as a pawl or dog for catching into the wheels and rotating them as the shaft is raised and lowered. This dog is seen with its projections 1 2 3, in fig. 6, and is so placed that its longest projection rests against the ratchet S, which ratchet has one notch *t* deeper than its others, so that when the dog drops into it, it allows the notch 2*d* to drop between the figures in type-wheel No. 2, thereby moving one figure simultaneously with the first, commencing at figure 1 to print and continue to figure 9. The movement of the dog drops into the deep ratchet, thereby moving the 0 in the first row and the figure 1 in the second, making 10, &c. The second type-wheel has one space between the figures cut deeper than the others, so that when 100, &c., is required to be printed, the dog *d* drops deeper in order that projection 3*d* will move the third row of figures. *e f* represent two dogs which are secured in the frame B, and lie horizontally upon the front and rear side of the said cylinder, and act as guides for keeping the figures to be printed in line. The indentation *t* in the ratchet S is for the purpose of carrying the dog *d* a little further back, so that when it drops it will be sure to clear the figures in the type-wheels 2 3, &c., but after having dropped the projection will occupy the space in the ratchet. X represents the guide-frame, which lies upon the base A¹, and which has a small slot, *n*, beneath which is a rubber strip, Z, for protecting the type. This frame can be moved out or in by means of the regulating strip X², which is slid in or out its groove in the base, so that one, or more numbers may be printed at one time, as desired. The paper to be printed is placed upon the guide X when the shaft O is up, as seen in fig. 1. The shaft is then forced down, which nearly

straightens the frame B, and causes the rollers to pass to the rear and take new ink, when the shaft O is again raised and the figures changed, by means of the dog before described, and the machine is ready for the next numbered papers. The small roller K is divided into three or more sections so that it will more easily revolve upon its plate M. This plate M, with its inked surface, is adjusted by means of its screw P, to revolve or remain stationary, as desired, and can be made to turn freely or otherwise, as may be necessary in the operation of the machine.

Having thus fully described my invention, what I claim as new, and desire to secure by Letters Patent, is—

1. The stamp-frame with its shaft and plate J, cylinder a, ratchet S, type-wheels v v v, frames B C, dog d, and dogs e f, all constructed and arranged substantially as and for the purposes set forth.
2. The arrangement of the arm E, plate F, roller-frame H, with rollers K R, and spring e, in combination with the revolving table M, and screw P, when used in the manner and for the purposes set forth.
3. The guide-frame X, and rubber Z, for regulating the printing of the type by means of its slide X², in the manner and for the purposes specified.

In testimony that I claim the foregoing, I have hereunto set my hand this fourth day of February, 1867.

SAMUEL W. SOULE.
